United States Patent Office.

DANIEL P. LEACH, OF FRANKLIN, INDIANA.

Letters Patent No. 96,015, dated October 19, 1869.

IMPROVEMENT IN CORN-PLANTER, SEED-SOWER, AND CULTIVATOR.

The Schedule referred to in these Letters Patent and making part of the same.

To all whom it may concern:

Be it known that I, DANIEL P. LEACH, of Franklin, in the county of Johnson, and in the State of Indiana, have invented certain new and useful Improvements in Combined Corn-Planter, Seed-Sower and Cultivator; and do hereby declare that the following is a full, clear, and exact description thereof, reference being had to the accompanying drawings, and to the letters of reference marked thereon, making a part of this specification.

The nature of my invention consists in the construction and general arrangement of a combined corn-planter, seed-sower, and cultivator, as will be herein-after fully set forth.

In order to enable others skilled in the art to which my invention appertains, to make and use the same, I will now proceed to describe its construction and operation, referring to the annexed drawings, in which—

Figure 1 is a longitudinal vertical section, and

Figure 2, a plan view of the machine, the handles being removed.

Figure 3 is a side view of a portion of the bed of the machine, showing the manner of attaching the handles and plow-beams.

A represents the bed of the machine, at the front of which are attached the knives.

One knife, B, is placed in the centre, and the other two, B' B', one at each side of the front end of the bed.

The side knives have their cutting-edges turned outward, as shown in fig. 2.

Near the front end of the bed A are placed two harrow-teeth, C, pointing downward, and placed opposite the space between the knives B and B'.

In rear of the harrow-teeth, on the upper side of the bed A, is an upright rod, D, pivoted, the upper end of said rod being bent at right angles.

On this bent portion of the rod D is placed a beam, E, which can be turned to either side of the machine.

In the beam E is a number of holes, in which are inserted vertical teeth a a.

A rod, F, and chain G, connect the beam E with the front end of the bed A, the team being hitched to a suitable point on the chain G.

A rope or chain, b, also connects the beam E with a cross-beam, I, connecting the two handles, so as to be within easy reach of the operator.

By this arrangement a gauge or marker is obtained for the purpose of making the rows the same width, and for the horse to come back on, so as to give the operator a better chance for doing his work, and for the convenient detachment for the operator to change it from side to side, and raise it over stumps and other obstructions without leaving his position or stopping his horse.

On each side of the bed A, at the rear end, is attached a plow-beam, H, which is curved outward and then inward, as seen in fig. 2.

To the outer end of the plow-beam H is secured the covering plow-blades J, the point of which is twisted inward, so as to throw the dirt inwardly.

The inner ends of the plow-beams H H having several holes through which the bolts pass, can be raised or lowered at will on the bed A, thus making the covering-plows penetrate more or less into the ground.

By changing the beams or bars H H, the plows will throw dirt outwardly, and by changing the plows they will form straight plows, to throw dirt both ways.

The handles K K are at their lower ends attached to the bed A, and can be moved back and forth on the same, so as to give the operator more or less room, as may be desired.

At a suitable point the handles are connected by the bar I, and from this latter a bar, L, braces the handles to the beam A.

The bars L L are adjustable, so that the handles can be raised or lowered to suit the operator.

At the rear end of the bed A is pivoted an open platform, M, which, at its rear end, is provided with two arms, projecting downward between which the roller N is pivoted. The platform is for the purpose of applying weight to suit the operator, and enable him to see the corn before it is covered.

The outer end of the platform is, by a rope or chain, c, connected with the bar I.

On the bed A is placed the corn-box O, in the bottom of which the bar d operates to carry the corn out and drop the saine.

This bar is provided with an adjustable slide, e, so as to regulate the amount of corn to be dropped each time.

In the rear side of the box O, where the slide or bar d passes through the same, is placed an adjustable vertical slide, f, having at its lower end a brush, as seen in fig. 1, so as to brush off any corn that may be on top of the slide or bar d, and only allow the required quantity to pass through.

On the rear side of the box O, exactly over the opening leading to the furrowing-plow P, through which the corn is dropped, is placed a valve, i, which prevents the corn from bouncing off the slide when the shoulder formed on the front portion of the bar d strikes the front side of the box. This shoulder, which is shown in fig. 1, prevents the bar d from going backward more than a certain distance.

The bar d may be operated either automatically or by hand. For this purpose there is placed on top of the bed A, a suitable distance in front of the box O, a shaft, g, which, at one end, is attached to a bar, h, that extends toward the rear.

On this bar is an arm, having at its lower end a wheel, R, said arm being adjustable, so as to be placed at any desired distance from the rear end of the bar *h*.

The shaft *g* is at or about its centre provided with an arm, *k*, to the upper end of which is pivoted a bar, *l*.

This bar is pivoted to a lever, *m*, the upper end of which is pivoted to a standard, *S*, on the bed *A*.

The lower end of the lever *m* is, by a nut, *n*, connected with the slide or bar *d*.

The point where the bar *l* and lever *m* are pivoted together can be changed in any manner desired, both being provided with a number of holes, through which the pivot-bolt may be passed.

To the arm *k* is attached an adjustable strap, *o*, the other end of which is attached to a spring, *p*, as seen in fig. 1.

When the machine is in motion, and the wheel *R* is moving out of one furrow, and consequently raised, the slide or bar *d* is drawn forward by the arrangement of devices just described, and as soon as said wheel drops into the next furrow, the spring *p* forces the bar *d* to the rear, allowing the corn to be dropped into the ground.

For the purpose of operating the dropper by hand, I attach to the rear end of the bar *h* an adjustable strap, *r*, the other end of which is attached to one of the handles *K*, so that the operator may, without changing the position of his hands, easily operate the dropper.

The furrowing-plow *P* furrows out the ground, and prevents trash from catching on the bottom and dragging the seed from its proper place.

This device may be used equally as well for a seed-sower as for a corn-planter.

The knives *B* and *B'* take up the stalks and other trash, and keep the machine to the ground.

Having thus fully described my invention, What I claim as new, and desire to secure by Letters Patent, is—

1. The arrangement of the knives *B* *B'* and teeth *C* *C*, on the front end of the bed *A*, all substantially as shown and described.

2. The arrangement of the adjustable and changeable plow-beams *H* *H* and changeable plows *J* *J*, constructed substantially as described, and for the purposes set forth.

3. The arrangement of the adjustable strap *r*, connecting the bar *h* with the handle *K*, substantially as and for the purposes herein set forth.

4. The valve *i*, constructed as described, and for the purposes set forth.

5. The arrangement of the handles *K* *K*, connecting-bar *I*, and bars *L* *L*, for the purpose of adjusting the handles in any suitable manner, substantially as herein set forth.

6. The arrangement of the bed *A* with handles *K* *K*, pivoted platform *M*, with roller *N*, wheel *R*, bar *h*, slide *d*, in box *O*, and devices for operating said slide, rod *D*, beam *E*, and teeth *a* *a*, all the parts being constructed and operating as specified.

In testimony that I claim the foregoing, I have hereunto set my hand, this 20th day of July, 1869.

DANIEL F. LEACH.
